FLAT SINGLE BED KNITTING MACHINE

Gustav Huber, Cleator, England, assignor to
Kangol Wear Limited, Cleator, England, a company of Great Britain

Application December 20, 1946; Serial No. 717,553
In Great Britain January 6, 1946

8 Claims. (Cl. 66—147)

1

This invention relates to improvements in flat single bed knitting machines of the type used for knitting berets and articles of similar shape formed of a number of sections.

Such machines knit the articles in continuous length with a few rows of plain knitting between the last section of one article and the first section of the next, a separation thread being knitted into these rows to indicate the position for severing the articles.

Owing to the shape of the articles the continuous length is much shorter on one edge than the other and this makes it desirable that the articles should be separated after one or a few articles have been knitted, this separation being effected by hand by the operative.

The object of the present invention is the provision of automatic means for separating or severing the articles as the length of fabric is knitted.

According to the invention a carrier supporting a knife is arranged to be reciprocated across the material below the front edge of the bed thereof at the appropriate time in the cycle of the knitting operations to cause the knife to sever the fabric at the plain rows of knitting separating one article from the next.

This invention is illustrated in and will be described with reference to the accompanying drawings in which:

Fig. 1 is a plan of the knife carrier also showing one end of the patterning mechanism, a portion of the needle bed and the cam box;

Fig. 2 is front elevation of the knife carrier;

Fig. 3 is a section on line 3—3 of Fig. 1;

Fig. 4 is a front elevation of the cam box showing means for connecting the knife carrier thereto;

Fig. 5 is an end elevation looking in the direction of arrow 4, Fig. 1 showing mechanism operated from the patterning mechanism for actuating the means for connecting the knife carrier to the cam box;

Fig. 6 is a front elevation of a bracket which controls the movement of the knife holder to bring the knife into the cutting position at the commencement of the cutting stroke.

The patterning cylinder A, cam box B, needle bed, and the sinkers c (shown in Fig. 3) which control the thread to the needles which are not shown, are all of usual construction and operate in known manner.

A rectangular bar D is arranged in front of and below the needle bed C being supported in suitable brackets secured to the frame of the machine. The knife carrier D¹ is slidably mounted

2

on the bar D so that it can be reciprocated from side to side of the machine in front of the sinkers c. The knife E is carried by a holder E¹ pivoted at d on the carrier D¹, the holder being normally held in the non-cutting position, i. e. the position shown in Fig. 3 and in full lines in Fig. 1 against the pressure of the spring e³ by the pivoted catch e, the tail of which projects forwardly from the holder. An arm E², on which is pivotally mounted a spring controlled member e⁴ with an inclined face, is affixed to the rectangular bar D, the inclined face being arranged in the path of the tail of the pivoted catch e. The knife E, the cutting edge of which lies in a horizontal plane, is arranged between two rotatably mounted horizontal discs or rollers e¹, which during the cutting stroke, when the knife E and knife holder E¹ are in the position shown in dotted lines in Fig. 1, press onto the fabric so that the portion of the fabric between them is held taut for the operation of the knife. The opposite end of the knife holder E¹ to that on which the knife E is mounted is formed with a forwardly projecting member e² adapted to engage an inclined face f on a stationary bracket F at the end of the bar D at which the carrier D¹ is located at the end of the cutting stroke.

The knife carrier D¹ is provided with a rearwardly extending arm d¹ the end of which embraces the rod B¹ on which the cam box B reciprocates. A two armed lever d² is mounted on the arm d¹ so that it can pivot in a horizontal plane, one end of the lever being formed with a hook or catch d³ and the other end d⁴ lying above a sliding bolt a. The lever d² is held in its inoperative position, i. e. the position shown in Fig. 1 by a light spring d⁵.

The cam box B is formed with an undercut recess b adapted to be engaged by the hook or catch d³ on the lever d² when the latter is moved about its pivot.

A disc or the like A¹ is secured on the end of the shaft A² of the patterning cylinder A so that it rotates therewith and a projection a¹ with an inclined face is formed on or secured to the periphery of the disc A¹. The rear end of the sliding bolt a lies in the path of the projection a¹ whereby on each revolution of the cylinder A and consequently of the disc A¹ the rear end of the sliding bolt a is engaged by the inclined face of the projection a¹ and the bolt is moved forward against the pressure of the spring a². The front faces a³ of the bolt a is inclined as shown in Fig. 5 and this face engages the end d⁴ of the lever d² when the bolt is moved forward by the projection

a^1 causing the lever d^2 to move about its pivot and bring the hook or catch d^3 into engagement with the recess b in the cam box B .

The position of the projection a^1 on the disc A^1 relative to the patterning cylinder A is such that it will engage the bolt a when the knitting of an article is completed and the knitting of the next article has commenced so that the rows of plain knitting between the two articles are in a position to be engaged by the knife E .

During the normal working of the knitting machine the parts of the severing mechanism remain inactive being at one end of the machine and in the positions shown in the drawings (full lines in Fig. 1). When the rows of plain knitting between a completed article and the commencement of the next article being knitted are in the same horizontal plane as the knife E the inclined face of the projection a^1 on the disc A^1 rotating with the patterning cylinder A engages the rear end of the bolt a and moves the latter forward causing its inclined face a^2 to raise the end d^4 of the pivoted lever d^2 and bring the hook or catch d^3 into engagement with the recess b in the cam box B thereby connecting the knife carrier D^1 to the cam box. Accordingly on the next traverse of the cam box B the knife carrier D^1 will be moved with it across the front of the machine. The catch or hook d^3 remains in engagement with the recess b in the cam box when the end d^4 of the lever d^2 moves out of contact with the bolt a as the spring d^5 is sufficiently light not to overcome the pressure of the face of the recess b on the catch or hook d^3 until the cam box comes to rest at the opposite end of the machine.

When the knife carrier D^1 has moved a short distance at the commencement of its travel the tail of the pivoted catch e engages the inclined face of the member e^4 carried by the arm E^2 whereby the catch is moved out of engagement with the knife holder E^1 allowing the latter to be moved by the spring e^3 into the position shown in dotted lines in Fig. 1, in which position the knife E will engage and sever the article as the knife moves across the machine. As the knife carrier D^1 reaches the end of its traverse the member e^2 of the knife holder E^1 engages the inclined face f of the bracket F whereby the holder is returned to its initial position and re-engaged by the catch e , the knife E being thus held in its non-cutting position i. e. the position shown in full lines in Fig. 1.

As the cam box B approaches the end of its travel the pressure between the recess b and the catch or hook d^3 decreases until the pressure of the spring d^5 is sufficient to move the lever d^2 and raise the hook out of the recesses thereby disconnecting the knife carrier D^1 from the cam box B . On the return movement of the cam box B its end engages the arm d^1 of the knife carrier D^1 and pushes the latter back to its initial position where it remains until the bolt a is again actuated by the projection a^1 on the disc A^1 of the patterning mechanism.

When an automatic severing mechanism such as hereinbefore described is employed in a knitting machine of the type to which the invention relates it is not necessary to knit a separation thread into the rows of plain knitting.

I claim:

1. In a flat single bed knitting machine of the type referred to the combination with the bed and patterning mechanism of the machine of a carrier adapted to be reciprocated across the

machine below the front edge of the bed, a knife supported by said carrier and means controlled by the patterning mechanism for causing the reciprocating of the carrier at the appropriate time in the cycle of operations to cause the knife to engage and sever the fabric.

2. In a flat single bed knitting machine of the type referred to the combination with the bed and patterning mechanism of the machine of a carrier adapted to be reciprocated across the machine below the front edge of the bed, a knife holder pivotally mounted on said carrier so as to be capable of oscillation in a horizontal plane, a knife supported by the knife holder, means controlled by the patterning mechanism for causing the reciprocating of the carrier at the appropriate time in the cycle of operations to cause the knife to engage and sever the fabric, and means for oscillating the knife holder at the commencement of the cutting stroke to bring the knife into its cutting position.

3. In a flat single bed knitting machine of the type referred to the combination with the bed, patterning mechanism and cam box of the machine of a carrier adapted to be reciprocated across the machine below the front edge of the bed, a knife holder pivotally mounted on said carrier so as to be capable of oscillation in a horizontal plane, a knife supported by the knife holder, a catch mounted on the carrier and operated by the patterning mechanism to connect the carrier to the cam box at the appropriate time in the cycle of operations when it is desired to sever the fabric whereby the carrier will be traversed across the machine and means for oscillating the knife holder at the commencement of the cutting stroke to bring the knife into its cutting position.

4. In a flat single bed knitting machine of the type referred to the combination with the bed, patterning mechanism and cam box of the machine of a carrier adapted to be reciprocated across the machine below the front edge of the bed, a knife holder pivotally mounted on said carrier so as to be capable of oscillation in a horizontal plane, a knife supported by the knife holder, a sliding bolt operated by the patterning mechanism at the appropriate time in the cycle of operations when it is desired that the fabric should be severed, a catch pivotally mounted on the carrier operated by the movement of the sliding bolt to connect the carrier to the cam box, and means for oscillating the knife holder at the commencement of the cutting stroke to bring the knife into its cutting position.

5. In a flat single bed knitting machine of the type referred to the combination with the bed, patterning mechanism and cam box of the machine of a carrier adapted to be reciprocated across the machine below the front edge of the bed, a knife holder pivotally mounted on said carrier so as to be capable of oscillation in a horizontal plane, a knife supported by the knife holder, a disc driven by the patterning mechanism, a projection on said disc, a sliding bolt operated by the projection at the appropriate time in the cycle of operations when it is desired that the fabric should be severed, a catch pivotally mounted on the carrier operated by the movement of the sliding bolt to connect the carrier to the cam box and means for oscillating the knife holder at the commencement of the cutting stroke to bring the knife into its cutting position.

6. In a flat single bed knitting machine of

the type referred to the combination with the bed, patterning mechanism and cam box of the machine of a carrier adapted to be reciprocated across the machine below the front edge of the bed, a knife holder pivotally mounted on said carrier so as to be capable of oscillation in a horizontal plane, a knife supported by the knife holder, a disc driven by the patterning mechanism, a projection on said disc, a sliding bolt operated by the projection at the appropriate time in the cycle of operations when it is desired that the fabric should be severed, a catch pivotally mounted on the carrier operated by the movement of the sliding bolt to connect the carrier to the cam box, a second catch normally retaining the knife holder in a position in which the knife is inoperative, a spring acting to move the knife holder to the knife into its cutting position and means for releasing the second catch at the commencement of the cutting stroke.

7. In a flat single bed knitting machine of the type referred to the combination with the bed, patterning mechanism and cam box of the machine of a carrier adapted to be reciprocated across the machine below the front edge of the bed, a knife holder pivotally mounted on said carrier so as to be capable of oscillation in a horizontal plane, a knife supported by the knife holder, a disc driven by the patterning mechanism, a projection on said disc, a sliding bolt operated by the projection at the appropriate time in the cycle of operations when it is desired that the fabric should be severed, a catch pivotally mounted on the carrier operated by the movement of the sliding bolt to connect the carrier to the cam box, a second catch nor-

mally retaining the knife holder in a position in which the knife is inoperative, a spring acting to move the knife holder to bring the knife into its cutting position, means for releasing the second catch at the commencement of the cutting stroke and means for returning the second catch to its operative position at the end of the cutting stroke.

8. In a flat single bed knitting machine of the type referred to the combination with the bed, patterning mechanism and cam box of the machine of a carrier adapted to be reciprocated across the machine below the front edge of the bed, a knife holder pivotally mounted on said carrier so as to be capable of oscillation in a horizontal plane, a knife supported by the knife holder, two horizontal rollers between which the knife is mounted and which press on the fabric to maintain it taut during the reciprocation of the carrier, a disc driven by the patterning mechanism, a projection on said disc, a sliding bolt operated by the projection, at the appropriate time in the cycle of operations when it is desired that the fabric should be severed, a catch pivotally mounted on the carrier operated by the movement of the sliding bolt to connect the carrier to the cam box, a second catch normally retaining the knife holder in a position in which the knife is inoperative, a spring acting to move the knife holder to bring the knife into its cutting position, means for releasing the second catch at the commencement of the cutting stroke and means for returning the second catch to its operative position at the end of the cutting stroke.

GUSTAV HUBER.
